ERECTION APPARATUS

Campbell Allen Harlan, Birmingham, and John M. Harlan, Detroit, Mich.

Application July 20, 1953, Serial No. 369,107

3 Claims. (Cl. 304—2)

The present invention relates to apparatus intended to facilitate the erection or assembly of overhead structure. A typical example is in the mounting of recessed lighting fixtures into ceiling recesses.

It is an object of the present invention to provide apparatus intended to facilitate the mounting of overhead devices characterized by the provision of substantially universal adjustment so as to bring about registration between the devices and the supporting structure therefor.

More specifically, it is an object of the present invention to provide a movable carriage having means thereon for elevating a device and for adjusting the device universally in a horizontal plane so as to effect its registration with supporting fixtures.

More specifically, it is an object of the present invention to provide a carriage having a hollow vertical column thereon, an elongated member movable vertically in the column, means for elevating the vertical member relative to the column, a swivel plate at the top of said elongated member, a frame movable rectilinearly on the swivel plate, and support means movable on the frame in a direction transverse to the direction of movement of the frame.

Still more specifically, it is an object of the present invention to provide apparatus as described in the preceding paragraph in which the support means comprises a pair of support members each of which is independently adjustable on the frame in a direction transverse to the direction of movement of the frame on the swivel plate.

It is a feature of the present invention to provide anti-friction means facilitating movement of the frame on the swivel plate and movement of the support means on the frame which includes guards designed to prevent separation between the parts.

Other objects and features of the invention will become apparent as the description proceeds, especially when taken in conjunction with the accompanying drawings, wherein:

Figure 1 is an elevational view of the erection apparatus.

Figure 2 is a plan view of the apparatus on an enlarged scale.

Figure 3 is an enlarged elevational view of the spring means associated with the vertical elongated member, with parts in section.

Figure 4 is a section on the line 4—4, Figure 3.

Figure 5 is a fragmentary view similar to Figure 4 illustrating a modification of the present invention.

Figure 6 is an enlarged section on the line 6—6, Figure 2.

Figure 7 is an enlarged section on the line 7—7, Figure 2.

Figure 8 is a fragmentary elevational view showing the mounting of the support means on the frame.

Figure 9 is an enlarged fragmentary elevational view of the support means and its mounting.

2

Figure 10 is a sectional view on the line 10—10, Figure 9.

The apparatus comprises a carriage 10 consisting of a platform 12 provided with supporting legs 14 having 5 wheels or casters 16 at their lower ends so as to provide for ready mobility of the apparatus. Rigidly mounted on the carriage 10 is a vertical column 18 which preferably is of square hollow cross-section. The column 18 extends downwardly below the platform 12 and is 10 rigidly fixed in position by support structure including braces 20.

Mounted for vertical movement within the column 18 is an elongated member 22 which is also formed of square cross-section, as best illustrated in Figure 4. 15 Means are provided for raising the elongated member 22 relative to the column 18 and this means preferably comprises spring units including spring housings 24 opening toward the column 18 and having flanges 26 welded or otherwise secured to the flat sides of the column 18. Within the spring housings 24 are spirally wound 20 springs 28 mounted on pins 30. The springs 28 are of a well known type adapted to apply substantial uniform force when unwound. Located within opposite sides of the column 18 at the open sides of the housings 24 25 are openings 32 that receive the free ends of the springs 28. At the free ends of the springs 28 are hook elements 34 adapted to extend into openings 36 provided in the opposite sides of the elongated member 22. As a result of this construction the springs 28 are adapted 30 to apply a substantial constant force tending to elevate the elongated member 22. The number of springs employed will of course depend upon the weight which is to be elevated, including the devices to be assembled in overhead construction, as well as the weight of the 35 elongated members 22 and the apparatus carried thereby.

Preferably, the elongated member 22 is of substantially smaller cross-section than the column 18 thereby leaving substantial clearance space as indicated at 40 in Figure 4. This clearance space provides room for the free end portions of the springs 28.

As best illustrated in Figure 5, suitable guide means may be provided to maintain the elongated member 22 uniformly spaced at the sides thereof with respect to the column 18. As seen in this figure the guide means are 45 illustrated as guide or bearing blocks 40. These guide or bearing blocks may be welded or otherwise secured adjacent the corners and adjacent the lower end of the elongated member 22, or alternatively, they may be secured 50 to the inner corners of the column 18. In a preferred embodiment of the invention the bearing blocks 40 are provided adjacent the lower end of the elongated member 22 and a second set of such bearing blocks is carried by the column 18 adjacent the upper end thereof.

55 At its upper end the elongated member 22 is provided with an outwardly extending radial wall 42 terminating in an upwardly extending annular flange 44 providing a cylindrical pocket 46 therein. Bearing means indicated generally at 48 is provided and a swivel plate 50 having a 60 depending cylindrical stem 52 is carried by said bearing. Wear plates 54 and 56 are provided to engage opposite sides of the balls 58 of the bearing structure and support the swivel plate 50 for angular adjustment about the vertical axis of the stem 52.

65 As best illustrated in Figures 2 and 7, a frame indicated generally at 60 is mounted on the swivel plate 50. Preferably, the swivel plate 50 includes longitudinally extending arms 62, and U-shaped brackets 64 carrying rollers 66 are secured to said arms 62 adjacent their outer ends. 70 The material of the swivel plate 50 is struck out to provide material for guards 68 including horizontally extend-

ing flange portions 70 adapted to overlie the rollers 66 for a purpose which will presently appear.

The frame 60 may conveniently be formed of longitudinally extending angle irons 72 connected at their ends by transversely extending angle irons 74. The angle irons 72, as best illustrated in Figure 7, include inwardly extending horizontal flanges 76 adapted to rest upon the rollers 66 and to extend beneath the guard flanges 70. As a result of this construction the flanges 70 prevent upward movement of the frame 60 or tipping of the frame due to localized concentration of weight thereon. Extending upwardly from the angle irons 72 are brackets 80 which may conveniently be formed of straps secured at their lower ends to the angle irons 72, as best illustrated in Figure 1, and twisted at their upper ends to provide flat horizontal support portions 82. The horizontal portions 82 of the pair of brackets adjacent either end of the angle irons 72 are interconnected by cross straps 84.

Mounted on the horizontal portions 82 of the brackets 80 are roller supports 86 each of which is of generally U-shaped cross-section and includes upwardly extending flanges 88 between which is journaled a roller 90. Each of the roller supports 86 also includes an upwardly extending guard 92 terminating in a horizontally extending guard flange 94 which overlies the adjacent roller 90.

Mounted for movement transversely of the frame 60 are a pair of article supporting members indicated generally at 96. The article supporting members 96 may comprise bars 98 herein illustrated as formed of wood but which may be of any suitable material. Mounted on the upper surface of the bars 98 are pads 100 which may be formed of rubber or the like and which engage the under surface of the article or device A carried thereby. Extending longitudinally beneath the bar 98 is an elongated inverted channel member 102, the ends of the channel member 102 being connected to the bar 98 by members 104 thereby leaving an elongated slot or space 106 between the lower surface of the bar 98 and the upper surface of the channel member 102.

As best seen in Figure 10, the guard flange 94 extends into the space 106 and retains the channel member 102 in position on the rollers 90. In addition, as will be readily apparent, members 104 constitute end abutments to limit movement of the supports 96.

The apparatus is capable of widely divergent uses but will be described in conjunction with the erection of articles such as lighting fixtures A adapted to be elevated and inserted into recesses in a ceiling. For this purpose it is necessary to provide exact registration between the article A and supporting structure provided therefor within the recess. Obviously, of course, the utility would be equally great if the lighting fixture were intended to be secured to supporting structure provided on the ceiling rather than in a recess provided therein.

The carriage 10 is readily mobile and may be moved to a position generally beneath the location of the fixture to be mounted. The strength and/or number of springs 28 interconnecting the hollow column 18 and the vertical elongated members 22 is selected so as to provide for vertical movement of the article when placed in position on the article supporting members 96. When the article approaches its intended position it will normally be somewhat out of alignment therewith either longitudinally, laterally, or angularly. Inasmuch as the frame 60 is longitudinally movable on the rollers 66 and the swivel plate 50 is angularly adjustable in a horizontal plane about the axis of the column 18, it is readily possible to adjust the article A so as to be in alignment with the mounting. The article supports 96 are independently adjustable and since the article normally rests freely upon the resilient pads 100, it is possible to effect fine adjustment of the article A by moving one or the other of the article supports 90 to bring the corresponding end of the article A into registration with the mounting structure on the ceiling.

While it is possible to connect the article supports 96 into a unitary sub-frame adjustable as a unit transverse to the length of the frame 60, it is found greatly preferable to provide for independent adjustment of the article supports 96. This is particularly true where the article to be mounted in overhead relation is a relatively long article since normally such an article will be connected to its overhead supporting structure first at one end and then at the other. With the present arrangement it is possible to bring one end of the article into exact registration with its supporting structure and to connect it thereto. Thereafter, the necessary small adjustments of the other end of the article may be made by independent adjustment of the remaining article support, which of course would be impossible if the two article supports were rigidly interconnected for unitary movement.

Inasmuch as the apparatus is designed to effect automatic lifting of the article it is apparent that after the article has been assembled with its ceiling support, effort is required to lower the vertically movable part of the apparatus. The springs may however, be selected such that this effort is only slightly greater than the actual weight of the article and this effort is applied only during lowering of the support structure in order to permit placement of a new article thereon. This of course is a much simpler operation than would be required if effort were required to elevate the article and retain it in elevated position while it was adjusted into registration with the supporting structure and attaching means were applied to secure the article in such structure.

If desired, means may be provided effective to retain the vertically movable portion of the apparatus in depressed condition prior to placement of an article thereon. Such means for example may comprise a pin such as illustrated at 110, carried by a chain or the like 112 and adapted to be inserted through an opening 114 in the column 18 and into a corresponding hole in the elongated element 22 which registers with the opening 114 when the supporting structure is in depressed position.

Instead of providing springs for elevating the vertically movable portion of the apparatus, it would be possible to employ power means such for example as a motor. However, the spring means illustrated herein have been found to be perfectly satisfactory and represent a simplification in structure as well as an economy in producing the apparatus, and accordingly, the spring means illustrated herein is preferred.

The drawings and the foregoing specification constitute a description of the improved erection apparatus in such full, clear, concise and exact terms as to enable any person skilled in the art to practice the invention, the scope of which is indicated by the appended claims.

What we claim as our invention is:

1. Apparatus of the character described comprising a generally rectangular plate having guide rollers rotatably mounted adjacent the corners thereof, said plate having portions extending laterally outwardly above and adjacent said rollers, an open rectangular frame having side members provided with laterally inwardly extending flanges resting on said rollers and underlying the said portions of said frame, said flanges and said portions cooperating to prevent tilting of said frame when a load is concentrated at one end thereof.

2. Apparatus of the character described comprising a substantially horizontal plate, brackets on top of and secured to said plate, rollers carried by and projecting above said brackets, said plate having laterally extending portions overlying and adjacent said rollers, and a frame adjacent said plate and having laterally extending portions resting upon and supported by said rollers, the laterally extending portions of said frame underlying and cooperating with the laterally extending portions aforesaid of said plate to prevent said frame from tilting relative to said plate.

3. Apparatus of the character described comprising a

substantially horizontal plate, a frame adjacent said plate, and means for supporting said frame upon said plate for movement relative thereto and operable to prevent the frame from tilting relative to said plate, including brackets mounted on top of said plate, rollers carried by and projecting above said brackets, and overlapping elements carried respectively by said plate and frame and overlying said rollers, certain of said overlapping elements resting upon and being supported by said rollers.
